UNITED STATES PATENT OFFICE.

CLARENCE A. ANDERSON, OF LINDSBORG, KANSAS.

TELEPHONE-EXCHANGE.

No. 858,363.

Specification of Letters Patent.

Patented July 2, 1907.

Application filed May 18, 1903. Serial No. 157,598.

To all whom it may concern:

Be it known that I, CLARENCE A. ANDERSON, a citizen of the United States of America, and a resident of Lindsborg, county of McPherson, and State of Kansas, 5 have invented certain new and useful Improvements in Telephone-Exchanges, of which the following is a specification.

My invention relates to telephone exchanges and has for its object certain improvements in party line exchanges.

My invention is illustrated in the accompanying drawings in which

Figure 1 is a front elevation of the switching mechanism used at each local station; Fig. 2 is a side elevation of the same; Fig. 3 is a plan; Fig. 4 is a face view of the contact supporting table traversed by the contact maker; Fig. 4^a is a modification of one of the contacts shown in Fig. 4. Fig. 5 is an edge view of Fig. 4; Fig. 6 is a section on line 6—6 of Fig. 4; Figs. 7 and 8 are 20 respectively elevation and section of the yielding supports under the armature lever of the operating magnets; Fig. 9 is an elevation of the front face of a calling box at the central office; Fig. 10 is an inside view of the box cover and the mechanism supported thereon; 25 and Figs. 11 and 12, taken together, are a diagram showing the central office and three local stations connected to a party line.

In the said drawings A is a plate upon one side of which is supported a switching mechanism and upon 30 the other side of which is a direct current generator G. The switching mechanism consists of a ratchet wheel B operated by a pawl B¹ on a lever B². The lever B² is secured to an armature B³ which is movable in either direction from its central or normal position by the 35 magnets M and M¹.

Secured to one pole of the permanent magnets of the generator G is a bracket G¹, and to the other pole is secured the bracket G². The bracket G¹, on one side of the plate A, is in metallic connection with a bracket 40 G³ on the opposite side of the plate. Secured to the bracket G³ are two sockets G⁴, and into these sockets project the cores of the magnets M and M¹. By means of set screws G⁵ the magnets M and M¹ are held at any desired vertical adjustment. The result of this construction is that the lower ends of the magnets M and M¹ are of the same polarity as that of the permanent magnet at the point of attachment of the bracket G¹. In a similar manner the bracket G⁶ is magnetically connected to the other pole of the generator G through the 50 bracket G². To the bracket G⁶ is pivoted the armature B³, which armature has a polarity opposite to that of the adjacent ends of the magnets M and M¹.

Secured to the bracket G⁶ are two short tubes B⁴ which may be held at any desired vertical adjustment 55 by means of nuts B⁵. The upper end of the tube B⁴ is closed by a plug B⁶ and the lower end is closed by an

adjusting screw B⁷. Inside of the tube B⁴, and passing through holes in B⁶ and B⁷, is a rod B⁸ which is held in its upper position by a spring B⁹. The upper ends of the rods B⁸ touch the lower face of the armature B³ and 60 serve to hold the said armature in its mid position at equal distances from the poles of the magnets M and M¹. By means of the screw adjustment of the tubes B⁴ the upper ends of the rods B⁸ may be vertically adjusted so as to bring the armature B³ to its required mid-position. 65 By means of the adjustment of the screws B⁷ the tension of the springs B⁹ may be varied.

Supported at a convenient place on the plate A are two insulated springs 60 and 61, the ends of which project adjacent to one end of the armature B³. These 70 springs are not normally in contact with each other but they are so arranged that when the armature B³ is attracted by the magnet M¹ they will be brought into electrical connection. Attracting the armature B³ by the magnet M does not affect the springs 60 and 61. 75

Supported in any convenient manner is a pin B¹⁰, one end of which projects under the pawl B¹. When the magnet M attracts the armature B³ the pawl B¹ engages the teeth of the ratchet wheel B¹ and moves the said wheel forward one step. When the armature B³ returns to its mid-position the said pawl engages the next tooth of said wheel and rests closely adjacent to the pin B¹⁰. When the armature B³ is attracted by the magnet M¹ the pawl B¹ rides over the pin B¹⁰ and is lifted out of engagement with the teeth of the wheel B. 80 85

Secured to the ratchet wheel B is a long and flexible contact maker P which sweeps over a certain space when the wheel B is moved. Lying in the path of the contact maker P are two plates of insulating material C and C¹, and between these is a metal plate 90. The 90 plate C is removed from the plate 90 a sufficient distance to permit the contact maker P to pass between them. Through the plate C is an opening or notch C² arranged to permit the contact maker P to pass from the upper face of C to contact with the metal plate 90. 95

Adjacent to the plates C and C¹ is a long and flexible spring 29, the free end of which lies adjacent to one end of the plates C and C¹ and rises to a position slightly above the upper face of C. In its normal position the contact maker P lies closely adjacent to the end of the 100 plate C and is held by the spring 29 slightly above that plate. When the contact maker P is advanced by a movement of the ratchet wheel B it moves off of the spring 29 and on the upper face of the plate C, over which it passes as the wheel moves forward. When the contact maker P reaches the opening C², it drops off of the plate C into contact with the plate 90. If, when in this position, the ratchet wheel B be returned to its normal position, the contact maker will pass between the plates C and 90, remaining in electrical contact with 105 110 115 120 125 130 the plate C and is free to be raised by the spring 29 to a position above the face of the plate C. The spring 29 is flexible enough to freely yield to the contact maker P when held down by the plate C, but the contact maker is still more flexible, and hence is easily raised by the spring 29 when no longer held down by the plate C.

On the upper face of the plate C is a contact strip or point 57 which is connected by a wire to a magnet M^2 hereinafter to be described. In the switching mechanisms of the different stations this contact point is at different distances from the normal position of the contact maker P. For example, at station No. 1 it would be one step of the ratchet wheel B from the normal position of P. For station No. 2 it would be two steps, and so on. Also on the plate C is a second contact strip or point 65 which is provided with an electrical connection hereinafter to be described. The contact 65 lies closely adjacent to the opening C^2 and is at the last position that the contact maker P occupies before it drops into connection with the plate 90. Also on the plate A is a magnet M^2 provided with an armature E, one end of which armature is marked 79. Adjacent to the magnet M^2 are three insulated contact springs 67, 68 and 78. When the armature E is actuated by the magnet M^2 , 79 makes electrical connection with 78, and also pushes 68 into electrical connection with 67. When the armature is retracted these electrical connections are broken. Also on the plate A is a magnet M^3 provided with an armature F which has a hook F^1 . When the magnet M^2 attracts its armature E, said armature is caught by the hook F^1 and held in its attracted position, which position holds contacts between 78 and 79, and between 67 and 68. When the armature F is attracted by the magnet M^3 , E is released from F^1 and the electrical contacts are broken.

Supported at a suitable place is a holding pawl F^3 for the ratchet wheel B, which pawl has a tail piece F^4 that lies adjacent to an extension F^2 on the armature F. When the ratchet wheel B is advanced by the pawl B^1 , this advance is held by the pawl F^3 . When the armature F is attracted by the magnet M^3 the extension F^2 strikes the tail piece F^4 and lifts the pawl F^3 out of engagement with the ratchet wheel. If the magnet M^3 operates simultaneously with the magnet M^2 , then the pawl B^1 will ride over the pin B^{10} and also release the wheel B so that it may be returned to normal position. This return is effected by a spring wrapped around the spindle of the wheel and shown at B^{11} in Fig. 2.

At the central office there is a box S having on its front face a crank S^1 , a numbered dial S^2 , and a pointer 64 for the dial. In the dial, and in the path of, the pointer 64, are a series of holes S^3 in which may be inserted pins. When a pin is inserted in one of these holes and the pointer moved, the said pointer will touch the pin in passing and make an electrical connection therewith and consequently with the dial. If several pins are placed in the holes, then the pointer will make a corresponding number of contacts.

On the inside of the cover of the box S is a gear S^4 which is connected to the spindle of the crank S^1 . The gear S^4 meshes with another gear S^5 to which is secured a star wheel S^6 . This star wheel has as many points as there are numbers on the dial S^2 . Pivoted on the inside of the cover of the box S is a lever J, the free end of

which is arranged to enter the spaces between the points of the star wheel S^6 . A spring J^1 holds the lever J against the star wheel but permits the said lever to vibrate when the star wheel is rotated as a result of turning the crank S^1 .

On a convenient part of the lever J is a projection 43 having a piece of insulation secured to one side of it. When the lever J is in its normal position this piece of insulation strikes a spring 54 and presses it into electrical connection with another spring 55. When the lever is moved outward by the rotation of the star wheel S^6 the electrical connection between these springs is broken. Located adjacent to the projection 43 are three insulated springs 42, 48 and 49. These springs are normally separated from each other and from the projection 43, but when the lever J is moved outward 43 makes an electrical connection with 42, and also pushes 48 into electrical connection with 49.

In arranging a telephone exchange I provide a central office from which one or more party lines may extend. Assuming one party line, I provide a calling box like the one described, a telephone set including receiver R, induction coil K, battery X, plugs V and W, spring jacks V^1 and W^1 , drop D, clearing out drop D^1 , and certain keys and connections as shown in the diagram. The diagram also shows a direct current generator G which may or may not be used as desired.

At each local station there is a switching mechanism like that described, a receiver R, hook H, induction coil K, bell ringing device Q, direct current generator G, and electrical connections as shown. The central office is connected to the local stations by a wire 27 having branches to each station, and by a ground connection. There are no other connections between the several stations, and it is one of my principal objects to provide a satisfactorily working exchange of the party line type which will have its connections reduced to one wire and ground connections.

Assuming that the subscriber at telephone station No. 1 wishes to talk to the subscriber at telephone station No. 3 he will proceed as follows: He first turns the crank of his generator G when a direct current flows as follows: G—20—21—22—ground to the central office—23—24—D—25—26—27—back to station No. 1—28—P—29—30—31—32—33—G. This operates the drop D and calls the operator at the central office who inserts the plug V in the jack V^1 and presses the key L. The subscriber removes his receiver R when the talking circuit is as follows: K at station No. 1—34—R—35—36—29—P—28—27—to the central office—26—V—37—38—L—39—R—40—K—23—ground back to station No. 1—22—H—K. The subscriber tells the central office that he wishes to talk to station No. 3 whereupon the operator places contact pins in holes marked "1" and "3" in the dial S^2 and turns the crank S^1 to within one step of a complete circle. At the first movement of the lever J the projection 43 comes into electrical connection with spring 42. It also closes 48 to 49 and opens connection between 54 and 55. When this happens a current flows as follows: X—41—42—43—44—23—ground to all of the local stations—22—45—M—M¹—46—28—27—back to the central office—26—V—37—47—48—49—50—51—52—X. The magnets M and M^1 are so wound that this current through them acts to increase the magnetic force of M and decrease that of M^1 .

M¹, the result of which is the advance of the ratchet wheels of the different stations and the consequent movement of the contact makers P from connection with the spring 29 to the plate C. This is repeated for 5 each point on the star wheel S², the number of which, by the preliminary movement, is sufficient to leave all of the contact makers on their contacts points 65.

When the pointer 64 strikes a pin in the dial S², which in this case is in the first hole and while the projection 10 43 closes the connection between 54 and 55, then the current flows as follows: X—41—53—54—55—56—47—37—V—26—27— to all stations—28—46—M¹—M—45—22—ground back to the central office—23—44—63—64—51—52—X. This is a current in the opposite direction 15 through these magnets and consequently results in moving their armatures in the opposite direction. The only effect of this is to close 60 to 61. As this occurs when the pointer 64 is at the first hole in the dial S², the contact maker P of the station No. 1 will be 20 the only one in connection with its contact point 57, consequently at this station a branch of the previously described current will go from 28—P—57—58—M²—59—60—61—62—21—22— where it joins the branch before described. The result of this branch is to actuate 25 M² and close 79 to 78, also to close 68 to 67, these connections being made for ringing and talking at the station at which they occur. The same operations are repeated at station No. 3 which is the only station having its contact maker P on its contact point 57 at the time the 30 pointer 64 touches the pin placed in the third hole of dial S². The same thing would occur for any other stations on the party line provided contact pins had been placed in other holes in the dial S².

With the contact makers P on the contact points 65 35 the operator presses the key N when a current flows as follows: X—41—53—54—55—56—47—37—V—26—27 to station No. 3—28—P—65—66—67—68—69—Q—70—71—H—22—ground back to the central office—23—44—72—73—N—51—52—X. This operates the ringing device at station No. 3 and calls the subscriber. It would also operate the ringing device at station No. 1 provided the subscriber at that station had returned his receiver to its hook. It would not operate the ringing devices at other stations because their magnets M² had 45 not been previously operated and consequently there would be no connection between 67 and 68. There is a branch of this ringing circuit that goes from 28 through the magnets M¹ and M, but as the direction of the current going over this branch is contrary to the operating 50 direction it is without effect. Instead of using the battery for ringing, the operator may accomplish the same result by pressing key N¹ and turning the crank of generator G when a current flows as follows: G—74—75—76—N¹—38—37— as before to ground—23—44—77—G.

55 With both receivers off of their hooks the talking circuit between stations is as follows: K at station No. 1—34—R—35—78—79—80—27 to station No. 3—80—79—78—35—R—34—K—H—22—ground back to station No. 1—22—H—K.

60 As soon as the central operator places the stations in connection with each other she inserts the plug W in the spring jack W¹, then, when the subscribers are through talking, they ring off as follows: —G—20—21—22—ground—23—81—W—82—D¹—37—V—26—27—

65 80—79—78—35—36—30—31—32—33—G. This noti-

fies the operator who turns the crank S¹ so as to advance the pointer one step to its normal position, and presses key N. Advancing the pointer 64 again sends an operating current through the magnets M and M¹ and moves all of the contact makers P to a position in which they 70 will drop into contact with their plates 90. When the key N is pressed a current flows as follows: X—41—53—54—55—56—47—37—V—26—27—28 of all local stations—46—M¹—M—45—22—ground—23—44—72—73—N—51—52—X. This attracts the armature to 75 M¹ and lifts the driving pawl clear of the ratchet wheel. It also closes 60 to 61 when a branch of the circuit just described goes from 28 to P—90—M³—59—60—61—62—21—22— at which point it joins the previous current. This last action attracts the armature of M³, releases the armature of M², and lifts the holding pawl from the ratchet wheel. As this occurs while the driving pawl is also lifted it leaves the ratchet wheel free to be returned to its normal position. During this return movement the connection is held through the magnet 80 M³ until the contact maker runs off of the end of the contact plate 90 and is lifted to its original position by the spring 29.

The calling device is shown with a dial having twelve holes and a star wheel having twelve points. 90 In this case the limit of the number of stations on the party line would be ten. By increasing the holes in the dial and the number of points on the star wheel any desired number of stations may be placed on the line. When the limit of the exchange is two less than the 95 number of points on the star wheel the contact 57 of the last station will be closely adjacent to the contact 65. Although I have shown and described an exchange particularly arranged for two stations less than the number of points on the star wheel, I can advantageously 100 make the number of points on the star wheel three or four more than the number of stations. When I do this I lengthen out the contact point 65 (as shown in Fig. 4^a) so that it will be in contact with P for two or three steps of the ratchet wheel. The contact plate 90 is also lengthened out so that P may move on it for two or three steps after passing from 65. The object of this 105 is to compensate for misses in the operation by which one switch falls one or two steps behind the others. Thus suppose 65 be lengthened out to an extent equal 110 to three steps of the contact maker, that the operator stops the initial movement of the pointer 64 three steps short of a complete rotation, and that this would leave the contact makers P on the contact points 65 close to the edge of the opening C². Then if one of the 115 switching mechanisms had missed one or two steps in its forward movement it would still have its contact maker on its contact point 65. Upon the completion of the three last steps of the pointer 64 all of the contact makers P would be upon the contact plate 90 though 120 not all at identical positions. Then by operating the releasing devices the switching mechanisms are returned to their normal positions and again are in unison with each other. It will be seen from this that the harmful effects of lack of synchronism are avoided by 125 lengthening the contact point 65, and that the subsequent synchronizing of the mechanism is accomplished by lengthening the contact plate 90 and the return of the mechanisms to their normal position.

The magnets on the switching mechanisms are 130

wound so that the different branches will have like resistances, the object of which is to prevent a branched circuit carrying more current over one branch than over the simultaneously operated branch.

5. The switching mechanisms are bridged across the line, which line consists of one wire and ground. It will be observed that the switching mechanisms are in complete control of the central office and that their operations are independent of anything that the subscribers may do. Also that the subscribers can not break into a line in use. As switching mechanisms at the local stations are usually inclosed in boxes this impossibility of the subscribers breaking into a talking circuit will be evident from the fact that removing his receiver and turning his generator crank are the only operations that he performs. If a subscriber not called removes his receiver when the line is in use he will find his connections broken between 78 and 79 because the magnets M^2 have been operated only at the stations called. If he should turn his generator crank when the line is in use he would find it without effect because the current from the generator passes through P and 29 and the connection between these two is broken by the first movement of the switching mechanism anterior to placing the line in use.

What I claim is:

1. The combination with a switching mechanism, means for advancing it step by step from its normal position, and electrical devices for releasing it so that it may return to its normal position, of a contact maker carried by said switching mechanism and arranged to close electrical connection for said electrical devices at a point in the latter part of the forward movement of said mechanism, and means by which said contact is held closed during two or more steps of the forward movement of said mechanism.

2. The combination with step by step mechanism, a propelling device therefor, and a holding pawl, of a magnet for releasing said mechanism from its holding pawl, and a normally open electrical connection for said magnet arranged to be closed by the forward movement of said mechanism and to be held during two or more steps thereof.

3. The combination with a switching mechanism, a propelling device therefor, a holding pawl, a magnet for releasing said mechanism from its holding pawl, and a signaling device associated with said mechanism, of a contact maker carried by said mechanism, a contact point in the path of said contact maker closely adjacent to the final part of its forward movement, a second contact point at the final part of said movement, an electrical connection from the first contact point to said signaling device, and a second electrical connection from said second point to said magnet.

4. The combination with a switching mechanism, means for advancing it from its normal position, and electrical devices for releasing it, of an electrical connection for said electrical devices closed by the latter part of the advance movement of said mechanism, and means by which such connection is held closed during two or more advance steps of said mechanism.

60. 5. In a telephone exchange, a central office, and a series of local stations connected together by a party line, a calling device located at the central office and provided with a numbered dial and a pointer therefor, a switching mechanism at each station, means whereby upon moving said pointer for a predetermined distance less than a complete rotation said mechanisms will be moved to connect selected stations telephonically to the party line, and means whereby upon completing the rotation of said pointer said mechanisms will be moved to a position from which they may be returned to their normal positions.

6. In a telephone exchange consisting of a central office and a series of local stations connected by a party line, a contact maker at each station and means for moving it to and from its normal position, means whereby each contact maker in moving in one direction engages two contact points and in moving in the opposite direction engages a third contact point, and means for controlling the movements of said contact makers from the central office.

7. The combination with a party line, a series of local stations, and a switching mechanism at each station, of means for simultaneously advancing the mechanisms step by step, a releasing device for each mechanism, means by which all of said mechanisms close electrical connections for their releasing devices at the same number of advance steps from their normal positions, and means by which such electrical connections are held closed for two or more advance steps whereby the accidental displacement of one of said mechanisms may be remedied so that all are simultaneously in position to be released.

8. The combination with a telephone station, and a switching mechanism, of a magnet and a centrally pivoted armature so arranged that the armature will be moved in either direction on its pivot according to the direction of the impulses sent through the magnet, means by which a movement of the armature in one direction operates said switching mechanism, means by which reverse movements of the armature serve both to place the station in a telephonic connection and to release the switching mechanism, and means by which the position of the switching mechanism controls the effect produced by any given reverse movement.

9. The combination with a party line, a series of local stations, a switching mechanism at each station, and a magnet for each switching mechanism, of means by which impulses in one direction through said magnet serve to control the selective operation of said mechanisms, additional means by which impulses in the reverse direction through said magnet serve to control the telephonic connections of said stations and also the release of said mechanisms, and means by which the telephonic connections and the release of the mechanisms are effective only at predetermined points in the advance of said mechanisms.

10. The combination with a telephone station, a switching mechanism, and a magnet, of means by which impulses in one direction through said magnet serve to control the advance of said mechanism, means by which impulses in the reverse direction through said magnet serve to control both the telephonic connection of the station and the release of the mechanism, and means by which the effective results of such reverse impulses are controlled by the advance position of said mechanism.

11. The combination with a telephone station, a switching mechanism, and a magnet, of means by which the advance position of the switching mechanism is controlled by the operation of said magnet in one direction, and means by which the telephonic connection of the station and the release of the switching mechanism are jointly controlled by the advance positions of the switching mechanism and the reverse operation of said magnet.

12. The combination with a telephone station, a switching mechanism, and a magnet provided with an armature movable in either of two directions according to the direction of impulses flowing through said magnet, of means by which a movement of the armature in one direction controls the advance movement of the switching mechanism, means by which the reverse movement of the armature controls the telephonic connection of the station when the switching mechanism is at one advanced position, and means by which a similar reverse movement of the armature controls the release of the mechanism when the mechanism is at a different advanced position.

Signed at Lindsborg Kansas this 11th day of May 1903.
